UNITED STATES PATENT OFFICE

ALBERT KOEBLE, OF IRVINGTON, NEW JERSEY, ASSIGNOR TO THE UNITED STATES PRINTING AND LITHOGRAPH COMPANY, OF BROOKLYN, NEW YORK, A CORPORATION OF OHIO

ILLUMINATED DISPLAY

Application filed July 15, 1931. Serial No. 550,968.

This invention relates to improvements in illuminated displays and has more particular relation to improvements in such displays as are intended to be suspended from a support on a wall such as a picture moulding or the like.

One of the several objects of the invention is to provide an illuminated display of an improved construction which may be shipped in a flat condition and instantly set up in condition for use without gluing, fastening or the like, and hang suspended when so set up in position on the wall to be clearly visible from all points in a room.

Another object is to so construct the illuminated display that it will hang in an elevated position slightly inclined downward to effect visibility from all points below the hanging level.

Another object of the invention is to provide a "knock-down" display of the illuminated type in which the light can be located in a collapsible box at the back of the display proper; this box having hinged back and sides and a scored top all in one piece and capable of being forced down flat on the display or extended to form a box for the light.

The invention also has other objects, all of which will be hereinafter more particularly set forth and claimed.

In the accompanying drawing forming part of this specification,

Figure 1 represents a perspective view of a display embodying my invention taken from the rear,

Figure 2 represents a front elevation of the same.

Figure 3 represents a detail top elevation of the flat blank from which the light box is constructed,

Figure 4 represents a vertical section of the display hung against the wall, and

Figure 5 represents a back view of the display collapsed.

Described in general terms the invention includes a flat front display panel suitably cut out for the passage of light at certain points and having a suitable advertisement figure, reading matter or the like printed or lithographed thereon.

The panel is intended to be suspended in an inclined position facing diagonally downward from the picture or wall moulding.

The light box which forms the back of the device is constructed in a wedge shape with the greatest depth at the top so that when the rear wall of this box is flat against the wall, the front display panel will assume an inclined position facing downward so that it is visible clearly from all points in a room below the level of the display.

Described in detail the invention provides first the front ornamental panel 1 of heavy cardboard which is formed with suitable advertising matter 2 in the form of a "cut out", through which the light may shine, or a picture on transparent paper over a cut out portion through which light from the light box 3 may shine.

This light box is formed from a single blank and provides an inclined back 4, two hinged sides 5-5 which are scored as at 6-6 where they join the back, a bottom 7 also scored as at 8 where it joins the back and a top 9 scored as at 10 along its length and at the back as at 12.

This top 9 is formed with an attaching flap 11 that is glued to the back of the front panel.

The bottom 7 is also formed with a similar attaching flap 16 also secured to the back of the front panel.

It will be seen that the sides 5 are wide at the top and narrow at the bottom, and that the result of this structure is that when the back of the light box is placed flat against the wall, the front panel will be held in an inclined position so that it may be seen from all points in the room.

The top 9 is also formed at the point of the scoring 12 with attaching tabs 13-13 stamped from the material of the back 4. These tabs are nailed to the top of the picture moulding on the wall to secure the display in position against the wall.

Suitable ventilating or heat exits 14 are formed in the sides and top. The top is also formed with a light opening 15 just the size of a lamp socket so that the bulb may be screwed up through the opening into the socket and thus held in position.

When the box 3 is extended for use it is held in this extended position by the sides which are forced into position and hold the back away from the front panel.

When the device is to be collapsed, the sides are pulled outward at their free edges, the top pulled up along the scoring 10 as shown in Figure 5 so that the two halves of the top lie vertically side by side and the back is pushed close to the front panel, the scoring 8 and 12 allowing this movement. The whole display is thus flattened out against the back of the front panel and may be readily shipped or mailed.

What I claim is:

In an illuminated display, the combination with a display panel having a transparent portion, of a collapsible light box constructed from a single piece of material comprising sides having free edges, a back flexibly connected to said sides, a top, and a bottom of less width than the width of said top, said top and bottom being flexibly connected to the back and at their forward edges being permanently and flexibly connected to said display panel, said top being scored midway in a plane paralleling said display panel so as to fold upon itself permitting the collapsible light box to be folded flat against said display panel, said top being formed with rearwardly projecting ears for attachment to a wall moulding.

In testimony whereof I affix my signature.

ALBERT KOEBLE.
